PRINTING PRESS ROLL SHIFTING MEANS

Harry H. Rawson, Spokane, Wash., assignor to
Washington Machinery and Supply Company,
Spokane, Wash.

Application November 17, 1933, Serial No. 698,451

2 Claims. (Cl. 101—248)

My invention relates to printing press roll shifting means and certain objects of the invention are to provide adjusting means whereby the rolls of a printing press may be turned and set with respect to the driving means so that, after first printing with one color, the printing of additional colors will conform and register with the colors previously printed. Further objects are to provide an adjusting means that is simple in construction, and easy and quick to operate, and which will give a very refined adjustment of the rolls. Still further objects are to provide adjusting means that is of general application and which may be applied to printing presses in various ways.

With the above and other objects in view which will appear as the description proceeds, the invention consists of the novel construction, adaptation, combination and arrangement of parts hereinafter described and claimed. These objects are accomplished by devices illustrated in the accompanying drawing; wherein:

Figure 1 is a view in side elevation of the device; Fig. 2 is a top plan view of the same with parts broken away; Fig. 3 is a view in central longitudinal section of the gear shifting means; and Fig. 4 is a view in central longitudinal section of the device for operating the gear shifting means.

Referring to the drawing throughout which like reference numerals designate like parts, the numeral 5 indicates a portion of a printing press frame whereon is journaled a horizontal drive shaft 6 on which is fixed a bevel gear 7. Said bevel gear meshes with another bevel gear, designated by the numeral 8, which is fixed on the lower end of a vertical shaft 9, and on which shaft is fixed an additional pair of spaced apart gears 10 and 11. The gear 11 drives another bevel gear 12 that is integral with a wide helical gear 13 which is revolvably mounted on a stub shaft fixed to the frame 5.

A narrow helical gear 14 meshes with the wide helical gear 13. The helical gear 14 is integral with a hollow hub 15, and another narrow helical gear 16 is made an integral part of said hub outside of the narrow gear 14. The outer helical gear 16 meshes with a wide helical gear 17 which is secured to a spur gear 18 by means of bolts 19 passing through slots 20 provided in the helical gear 17. A type or plate carrying roll 21 has its end axle 22 journaled through the frame 5, and the spur gear 18 is keyed or otherwise fixed on said end axle. The spur gear 18 meshes with another spur gear 23 fixed on an end

axle which is journaled through the frame 5 and fixed to a press roll 24 which engages the type roll 21. A paper 25, upon which the printing is done, passes between the rolls 21 and 24.

The gear shift or adjusting arrangement, shown in Fig. 3, embodying the narrow inner and outer helical gears 14 and 16 respectively and forming a part of the hollow hub 15 is a very important feature of my invention. Said hollow hub is revolvably mounted on a sleeve 26 one end of which is fixed through the frame 5. A rod 27 extends slidably through said sleeve and the frame, and the end 28 of the hollow hub is journaled on said rod. A thrust bearing 29 is mounted on said rod against the inside of said hub end and two nuts 30 form a bearing for the outside of said hub end. In this arrangement it will be apparent that the hollow hub 15 revolves both on the sleeve 26 and on the rod 27, and said rod may be turned and slidably moved back and forth thus carrying the hollow hub with it.

The detail means for turning and slidably moving the rod 27 is shown in Fig. 4 wherein a hand wheel 31 is fixed on its end. The end portion of said rod is threaded at 32 and said threaded portion extends through an internally threaded bearing member 33 which is fixed to the frame 5. Said bearing is split and a bolt 34 extends through the split portion whereby same may be clamped tightly against the rod to retain same in a stationary position as will be understood. It will be apparent that by turning the wheel 31, the rod 27 may be slidably and revolvably moved back and forth as desired and the hub 15 together with its gears 14 and 16 will be moved back and forth with it.

When the hub 15 is moved back or forth its narrow gear 14 will be slidably moved along the face of the wide gear 13. Both of said gears, having helical teeth or teeth which slant with respect to their axes, the gear 14 will be turned, it being assumed that the gear 13 remains stationary. This will turn the hub 15 and gear 16 which gear will turn the gear 17 thus turning the type roll 21, and will also turn the roll 24 through the medium of the gears 18 and 23. This arrangement provides a quick, easy and refined means for adjusting the rolls relative to each other and with respect to the drive shaft 6. Said rolls may thus be either set forward or backward by turning the handle 31, and when they are set to the required position the bolt 34 is tightened thus retaining them in the desired position. A coarse adjustment of the rolls may first be made by loosening the bolts 19 and turn-

ing the gear 17 whereby the slots 20 will slidably move on said bolts which may then be tightened.

My device is of practical use in setting type or plate rolls for the purpose of lining up and matching colored printwork where one or more colors have previously been printed and it is desired to print another color. It provides means whereby the additional color is caused to print at the correct place instead of being too far above or below the correct place which has often been the case. While I have described the gears 16 and 17 as being helical, same may be spur gears if desired. The teeth of the gears and the gears themselves may be varied as desired, it being understood that my device is of general application. For the purpose of brevity, in the claims the system of gears between the drive shaft 6 and the hub 15 will be termed the "driving gears", and the system of gears between said hub and the printing rolls will be termed the "driven gears".

Having thus described my invention, what I claim and desire to secure by Letters Patent is:

1. In a printing press comprising a frame having a pair of printing rolls mounted thereon, the combination with a system of driving gears one of which is a helical gear, and a system of driven gears arranged to rotate the printing rolls, of adjusting means for the rolls comprising a hol-

low hub having a pair of gears formed thereon in spaced apart relation, a rod slidably and revolvably mounted through the frame, said hub revolvably mounted on said rod and arranged to slidably move therewith, a threaded connection between the rod and frame, means for manually revolving the rod, one of the gears on the hollow hub having helical teeth meshing with the teeth of the helical gear of the driving gear system, the other gear meshing with one of the gears in the system of driven gears and said driven gears inter-meshed and connected to the printing rolls whereby the rotative position of both rolls is adjusted when the rod and hub is revolved.

2. In a printing press having printing rolls mounted thereon, the combination with a system of driving gears one of which is provided with helical teeth, and a system of driven gears arranged to rotate the rolls, of adjusting means for the rolls comprising a pair of integrally connected gears, one of said gears having helical teeth meshing with the gear having helical teeth in the driving gear system, the other gear meshing with one of the driven gears for rotating the rolls, and one of said driven gears adjustably connected with another driven gear.

HARRY H. RAWSON.
